UNITED STATES PATENT OFFICE

2,630,852

MECHANICAL IMPACT TOOL

Allen F. Myers, Kansas City, Mo., assignor to
John A. Stovall, Mountain Home, Ark.

Application June 2, 1950, Serial No. 165,771

5 Claims. (Cl. 153—48)

1

This invention relates generally to improvements in power-driven impacting tools and, more particularly, to tools designed for use in straightening and smoothing sheet metal, and for various other purposes.

The primary object of the instant invention is to provide a power-driven tool, which is compact and easily handled without placing any strain on an operator or requiring any manual power.

Another object of this invention is to provide a power-driven impact tool, which is extremely light and portable in nature and which is equipped with means for eliminating undue strain upon the parts of the tool and upon the operator.

Another object of this invention is the provision of a tool of this type, wherein the heads are readily interchangeable.

These and ancillary objects and structural features of merit are attained by this invention, the preferred embodiment of which is set forth in the following description and illustrated in the accompanying drawings, wherein:

Figure 1 is a view in perspective of a tool, constructed in accordance with this invention, and illustrating the same in an operational environment;

Figure 2 is a side elevational view of the tool;

Figure 3 is a side elevational view thereof with the protective hood or cover removed;

Figure 4 is a transverse, sectional view taken on line 4—4 of Figure 3.

Figure 5 is a transverse, sectional view taken on line 5—5 of Figure 3; and

Figure 6 is a longitudinal, sectional view taken on line 6—6 of Figure 5.

Referring now more particularly to the drawings, the tool 10 includes a rotary power shaft 12, which is rotatably housed in a tubular housing 14. The power shaft 12 is connected by a flexible cable or connection 16 with an electric motor or suitable prime mover 18, the motor being mounted on a wheel-mounted base 20. The motor 18 may be positioned at any point remote from the tool, and power is transmitted to the drive shaft 12 through the flexible connection 16.

An eccentric 22 is fixed on the projecting end 24 of the drive shaft 12 and is provided with an integral balanced weight 26. A pin 28 extends laterally from the eccentric, and the upper sleeve end 30 of a connecting crank link 32 is mounted on the projecting portion of the pin and held thereon by a cotter pin 34. The sleeve 30 is disposed on a bushing 36, as seen in Figure 6.

Guide means 38 is provided for the removable

2

heads carried by the connecting crank link 32. The guide means 38 includes a sleeve 40 within which a bushing 42 is positioned. An apertured flange 44 projects laterally from the upper end 5 of the sleeve 40, and a fastener 46 is carried thereby. The fastener is secured to the lateral extension 48 of a collar 50, which is concentrically clamped on the housing 14.

The head or striker member 52 is bifurcated 10 at its upper end and is formed with branches 54 and 56. The lower apertured end of the link 32 is disposed between the branches, and the branches are suitably apertured to receive a floating wrist pin 58, which is mounted in the lower 15 end of the link.

The upper end of the sleeve is formed on its inner surface with upwardly and outwardly slanting diametrically opposed slots 60 and 62, whereby, as seen in Figure 5, the link 32 can freely 20 move upwardly and downwardly in the sleeve to reciprocate the striker member 52 in response to the rotation of the eccentric 22 on the rotary drive shaft 12.

A compensating spring 64 is coiled on the 25 sleeve 40 and abuts against the shoulder 66 formed on the upper end thereof, the spring extending beyond the lower end of the sleeve and being concentric with the striker member 52. The spring 64 functions as a shock absorber to 30 compensate for the impact of the head or striker member 52 against the work piece and also assists in the straightening of the work when pressed against the work.

A concavo-convex hood or shield 68 is formed 35 with arcuate flanges 68 and 70, the flange 68 being fitted on the upper end of the sleeve 40 and fastened thereto by a screw 72, and the flange 70 being mounted on the clamping collar 50 and fastened thereto by a screw 74.

In use, the tool can be held in one hand by an 40 operator, the operator grasping the housing 14, and the other hand of the operator can be positioned on the head 66 to hold the impacting end of the tool in engagement with the work, such as the side of a vehicle 76. As the shaft 12 is 45 driven through the motor 18, the eccentric is rotated to reciprocate the link 32, and the striking member 52 carried thereby.

Of course, various heads may be employed, 50 such as peens, hammers, saws or the like. To effect a substitution of the heads, it is only necessary to remove the fastener 46 from the extension 48 of the collar 50, whereby the guide sleeve 40 may be removed and the pin 58, which is 55 loosely mounted, can be withdrawn. Various

types of hammers can then be substituted for the striking member 52 without the necessity of removing the cotter pin 34 or disturbing the connecting link 32. Thus, the heads or striker members 52 are readily and easily interchangeable.

Having thus described the invention, what is claimed is:

1. A power-driven impact tool comprising a sleeve like housing, a rotary drive shaft in said housing and having one end projecting from the housing, an eccentric disposed on said end of the shaft, a balanced weight associated with said eccentric, a link pivoted at one end to the eccentric, a guide sleeve detachably carried by the housing and disposed at right angles thereto, said link being disposed within the sleeve, a head carried by the other end of the link and slidably housed in the sleeve for reciprocating movement from one end thereof, means releasably connecting said head to the link said means being retained in position by the sleeve, and a spring coiled around said sleeve and projecting beyond the end of the sleeve from which the head operatively projects, said spring being adapted to bear against a work piece, and a concavo-convex shield surrounding said end of the shaft and eccentric, said shield being secured to the housing and the sleeve.

10

15

20

25

2. The combination of claim 1, wherein said sleeve is formed with diametrically opposed vertical slots in its upper end forming guides for the link in its reciprocating movement in the sleeve.

3. The combination of claim 1, wherein said connecting means includes a floating wrist pin transversely inserted through the adjoining ends of the link and head, said head being bifurcated and said link end being pivoted on the pin between the bifurcations.

4. The combination of claim 1, wherein said sleeve is formed with a lateral flange and a clamp is mounted on the housing and affixed to the flange for supporting the sleeve.

5. The combination of claim 1, wherein said sleeve is formed with an annular shoulder seating the inner end of the spring.

ALLEN F. MYERS.
